OLAF A. JOHNSON AND ROLLIE E. LINGREN, OF MINNEAPOLIS, MINNESOTA, ASSIGNEES
TO STORM MANUFACTURING CO., INC., OF MINNEAPOLIS, MINNESOTA, A CORPORATION OF MINNESOTA

CYLINDER FINISHING TOOL

Application filed August 12, 1929. Serial No. 385,130.

Our invention has for its object the provision of an extremely simple and highly efficient cylinder finishing tool intended for general use, but especially well adapted for use to polish and finish the cylindrical surfaces of new or rebored engine cylinders or for trueing up slightly worn or scored cylinders.

To the above end, generally stated, the invention consists of the novel devices and combinations of devices hereinafter described and defined in the claims.

In the accompanying drawings, which illustrate the preferred form of the invention, like characters indicate like parts throughout the several views.

Referring to the drawings:

Fig. 1 is a side elevation of the improved tool extending into one of the cylinders of an engine block shown in central longitudinal section;

Fig. 2 is a view of the improved tool principally in central longitudinal section;

Fig. 3 is a view partly in plan and partly in transverse section taken on the line 3—3 of Fig. 2 and further illustrating, by means of broken lines, the cylinder wall; and

Figs. 4 and 5 are detail views in transverse section taken on the lines 4—4 and 5—5, respectively, of Fig. 2.

For the purpose of illustrating the finishing tool in working position, there is shown in Fig. 1 of the drawings an engine cylinder block 6 with the tool extending into the cylinder thereof. As shown, the improved tool is carried and rotated by a shaft 7 to which it is detachably applied by a ball and socket coupling 8. It may be assumed that the shaft 7 is driven by a portable electric motor, not shown.

The improved tool includes a long body member 9 that is square in cross-section and provided with a longitudinally extended axial seat 10, which extends completely through said member and is also square in cross-section. This body member 9, at its outer end portions, has integrally formed therewith outwardly and axially projecting screw studs 11, and is longitudinally split through its axis and seat 10. The sections

of the body member 9 are rigidly but detachably connected in assembled relation by a screw cap 12 and a screw collar 13 applied one to each of the studs 11. Integrally formed with the outer end of the screw collar 13 is a hollow head 14 of cylindrical form axially aligned with the body member 9, and the outer end of which is closed. Formed in the walls of the head 14 is a pair of diametrically opposite passageways 15, which extend longitudinally of said head.

The socket member of the coupling 8 at its outer end, is internally rabbeted and telescoped onto the outer or closed end of the head 14 and detachably secured thereto by a pin 16. By reference to Figs. 1 and 2, it will be noted that the ball member of the coupling 8 is detachably secured by a bayonet joint 8' to the socket member thereof.

The improved tool is provided with a plurality of long hones or grinding stones 17 that are relatively narrow and circumferentially spaced about the axis of the body member 9, equal distances apart and parallel to the axis of said member. As shown, there are four of these hones removably mounted in individual channel-shaped grippers 18 and rigidly held therein by cement or other fastening means. Each gripper 18 is carried by a pair of plungers 19 to the outer ends of which the backs of said grippers are rigidly secured. These plungers 19 are round in cross-section and mounted in bore-like seats in the sections of the body member 9 for endwise sliding movement and project at right angles to the axis of the seat 10. Formed in the inner face of each plunger 19 are oblique teeth 20 that project into the seat 10 in the body member 9.

The plungers 19 are simultaneously and positively projected to carry the hones 17 into contact with the cylindrical surface of a cylinder or retracted to carry the same out of contact therewith by an endwise movable non-rotary shift bar 21. This shift bar 21, which is square in cross-section, is mounted in the seat 10 for endwise sliding movement, and as both the seat 10 and bar are square in cross-section, said bar is held from turning in said seat about the longitudinal axis

of the tool. Oblique teeth 22 are formed on each flat face of the bar 21 and mesh with the teeth 20 on the plungers 19. The teeth 20 and 22 extend at angles of substantially 45°, and the cam action, between the intermeshing teeth 20 and 22, is such that an endwise sliding movement of the bar 21 will either project or retract the plunger 19 depending on which way said bar is moved.

By removing the cap 12 and sleeve 13 from the body member 9, the sections of said member may be separated through the seat 10 to permit the removal of the bar 21 from said seat. This removal of the bar 21 separates the teeth 22 from the teeth 20 on the plungers 19 and permits said plungers to be endwise removed from the sections of the body member 9. Obviously, the distance the plungers 19 may be endwise moved by the bar 21 during its endwise movement is equivalent to the pitch of the teeth 22. The rows of teeth 20 on the plungers 19 permit said plungers to be endwise adjusted in the body member 9 to position the hones 17 different distances from the axis of the tool before the bar 21 is placed in its seat 10 to adjust said tool for cylinders of different diameters. The longitudinal rows of teeth 22 on the bar 21 also permit said bar to be placed in its seat 10 in different longitudinal positions with certain of its teeth 22 in mesh with the teeth 20.

A micrometer is provided for adjusting the feed device for the hones 17, which includes the bar 21, plungers 19, and intermeshing teeth or cam connections 20 and 22. This micrometer includes a sleeve 23 and a co-operating nut-acting member 24 within said sleeve and having screw-threaded engagement therewith. Said sleeve 23 surrounds the head 14, is concentric thereto and held against axial movement by the coupling 8 and collar 13 between which it is mounted. The nut-acting member 24 is in the form of an oblong block, which extends through the passageways 15, is held thereby against turning movement about the axis of the tool during the rotation of the sleeve 23 thereon, but is free for longitudinal sliding movement in said 50 passageways during the axial adjustment of said nut-acting member by the rotation of the sleeve 23 thereon. This nut-acting member 24 is detachably secured to the bar 21 by a stem 25, which extends through an axial bore in said nut-acting member, is rigidly secured thereto by a pin 26 and has screw-threaded engagement with one end of the bar 21 at the axis thereof.

The periphery of the sleeve 23 is knurled to afford a suitable gripping surface by which it may be turned on the nut-acting member 24. Formed on the periphery of the sleeve 23, at the inner end thereof, is an annular scale 27 and indicated on the collar 13 is a co-operating zero point. Each grad-

uation of the scale 27 represents, as shown, two one thousandths and during the feeding of the hones 17 to their work by the rotation of the sleeve 23, said hones may be set to cut a predetermined depth.

By reference to Fig. 5, it will be noted that the apexes of the teeth 22 substantially contact with all of the walls of the seat 10 with the exception of opposite portions thereof in one section of the body member 9. The seat 10 at this point is increased in width to leave considerable clearance between said seat and the apexes of the teeth 22 so as to prevent binding in case the two sections of the seat 10 do not properly align when the sections of the body member 9 are connected by the cap 12 and collar 13.

To finish the internal wall of a cylinder, the hones 17 are first retracted, by operating the sleeve 23, to a diameter slightly less than that of the cylinder to permit said tool to be inserted axially therein. After the tool is positioned in the cylinder, the hones 17 are projected against the wall of the cylinder by turning the sleeve 23 in an opposite direction with sufficient pressure to cause said hones to produce a cutting action. As the walls of the cylinder are cut away by the hones 17, said hones are fed to their work by the rotation of the sleeve 23. The scale 27 on the sleeve 23 will indicate when the cylinders have been cut the required number of thousandths to true the same up and to the desired diameter. During the rotation of the tool in a cylinder by the shaft 7, said tool may be moved axially up and down in the cylinder to finish the same throughout its entire length and to a constant diameter.

The plungers 19 by their toothed engagement with the bar 21 always keep the hones 17 a uniform distance from the axis of the tool and without end play so that the outer or cutting faces of said hones move in the same orbit and form a true cylinder.

What we claim is:

1. A tool of the class described mounted for orbital movement and having a feed device for changing the orbit of the tool comprising an endwise movable non-rotary shift bar, a non-rotary endwise movable plunger, a cam-connection between the bar and plunger whereby a reciprocatory endwise movement of the bar will impart reciprocatory endwise movement to the plunger, and a micrometer for endwise adjusting the bar comprising a rotatable sleeve held against axial movement, and a co-operating relatively fixed nut-acting member having screw-threaded engagement therewith.

2. A tool of the class described mounted for orbital movement and comprising a body member having an internal seat, said body member being longitudinally split through said seat, a coupling applied to each end of the body member for connecting the sec-

tions thereof, a non-rotary shift bar mounted in said seat for endwise movement, a plunger mounted in the body member for endwise sliding movement, a cam connection between the bar and plunger, a hollow head on one of the couplings and having a pair of diametrically opposite passageways, and a micrometer for endwise adjusting the bar comprising a nut-acting member detachably applied to the bar, slidably mounted in said passageways and held thereby from turning about the axis of the tool, and a rotatable sleeve having screw-threaded engagement with the nut-acting member and held against axial movement in respect to the tool whereby the rotary movement of the sleeve will impart an endwise movement to the bar.

3. A tool of the class described mounted for orbital movement and comprising a body member having an axial seat, an endwise movable shift bar mounted in the seat and having a plurality of circumferentially spaced flat faces, said bar having on each face oblique teeth, circumferentially spaced abrading members having plungers mounted in transverse seats in the body member and having oblique teeth that mesh with the teeth on the bar, and means for endwise adjusting the bar.

4. A tool of the class described mounted for orbital movement and comprising a body member having an axial seat extending therethrough that is square in cross-section, an endwise movable square shift bar mounted in the seat and held thereby against rotation, said bar having oblique teeth on each face, circumferentially spaced abrading members having plungers mounted in transverse seats in the body member and having oblique teeth that mesh with the teeth on the bar, and means for endwise adjusting the bar.

5. A tool of the class described mounted for orbital movement and comprising a body member having an axial seat, said member being longitudinally split through its axial seat, an abrading member having a plunger mounted in a transverse seat in the body member, a shift bar mounted in the seat, intermeshing operating connections between the bar and plunger that are separable by a lateral movement of the plunger from the bar, means for endwise adjusting the bar, said bar comprising two detachably connected sections that are separable to disconnect the operating connections and permit the bar to be removed from its seat by a lateral movement, said transverse seat being constructed to hold the plunger against lateral removal therefrom.

6. A tool of the class described mounted for orbital movement and comprising a body member having an axial seat, said member being longitudinally split through its axial

seat, an abrading member having a plunger mounted in a transverse seat in the body member, a shift bar mounted in the seat, intermeshing operating connections between the bar and plunger that are separable by a lateral movement of the plunger from the bar, means for endwise adjusting the bar, said bar comprising two sections that are separable to disconnect the operating connections and permit the bar to be removed from its seat by a lateral movement, and couplings connecting the sections of the body member at the ends, said transverse seat being constructed to hold the plunger against lateral removal therefrom.

7. The structure defined in claim 6 in which one of the couplings is an external sleeve which leaves the seat in the respective end of the body member unobstructed and the other a cap which closes the respective end of the body member, each of said couplings having screw-threaded engagement with the body member.

8. A tool of the class described mounted for orbital movement and comprising a body member having an internal seat, said body member being longitudinally split through said seat, a coupling applied to each end of the body member for connecting the sections thereof, a non-rotary shift bar mounted in said seat for endwise movement, a plunger mounted in the body member for endwise sliding movement, a cam connection between the bar and plunger, a hollow head on one of the couplings and having a pair of diametrically opposite passageways, a driven shaft, a ball and socket coupling attaching said shaft to the head, and a micrometer for endwise adjusting the bar comprising a nut-acting member on the bar, slidably mounted in said passageways and held thereby from turning about the axis of the tool, and a rotary sleeve surrounding the head and held against axial adjustment by this coupling on the head, said nut-acting member and sleeve being connected by screw-threads whereby rotary movement of the sleeve will impart an endwise movement to the bar.

9. The structure defined in claim 8 in which the ball and socket coupling is detachably applied to the head to permit the removal of the sleeve from the tool.

10. A tool of the class described mounted for orbital movement and comprising a body member having an axial seat, a non-rotary endwise movable shift bar mounted in said seat, said member having a head with diametrically opposite slots, a nut-acting member extending through said slots, a stem having screw-threaded engagement with the bar at the axis thereof and extending through an axial seat in the nut-acting member and detachably secured to said member, means having threaded engagement with the nut-acting

member and operable to axially adjust said member and the connected shift bar, an abrading member, and an operating connection from the bar to the abrading member.

5 In testimony whereof we affix our signatures.

OLAF A. JOHNSON.
ROLLIE E. LINGREN.
